UNITED STATES PATENT OFFICE.

WILLIAM EDWARD BOEHCK, OF JERSEY CITY, NEW JERSEY, ASSIGNOR TO NEW YORK REVOLVING PORTABLE ELEVATOR COMPANY, OF JERSEY CITY, NEW JERSEY, A CORPORATION OF NEW JERSEY.

SECTIONAL PORTABLE ELEVATOR.

1,105,956.

Specification of Letters Patent.

Patented Aug. 4, 1914.

Application filed April 19, 1913. Serial No. 762,237.

To all whom it may concern:

Be it known that I, WILLIAM EDWARD BOEHCK, a subject of the Emperor of Germany, residing at Jersey City, in the county 5 of Hudson and State of New Jersey, have invented certain new and useful Improvements in Sectional Portable Elevators, of which the following is a specification, reference being had to the accompanying 10 drawings.

This invention relates to improvements in portable elevators or tiering machines; and an object of this invention is to provide a portable elevator or tiering machine the 15 height of which may be varied for any desired purpose, such as that the machine may be drawn through doorways in passing from room to room of the warehouse or other place in which it is used.

20 In the drawings illustrating the principle of this invention and the best mode now known to me of applying that principle, Figure 1 is a side elevation of a portable elevator or tiering machine embodying this 25 invention; Fig. 2 is a front elevation or view taken in the direction of the arrow A in Fig. 1; and Fig. 3 is a detail of the sheave bracket.

The base *a* is mounted upon the truck *b*, 30 which is provided with two rear wheels *c* and a caster or steering wheel *d*. The machine is drawn from place to place by means of a handle *e* fastened to the mounting of the steering-wheel. From the base *a* there 35 rises a pair of side standards *f* which constitute side members of a vertical main guide-frame which is stiffened and strengthened by means of horizontal and inclined braces *g*, *h*. Centrally-disposed between the 40 side frame-members *f* is a subframe *i* the lower end of which is supported by the base *a* and the upper end of which is fastened to one of the horizontal brace-members *g*. In this subframe *i* there are mounted a 45 windlass-drum shaft *j*, an intermediate shaft *k* and an operating shaft *m*. Upon the lowermost or windlass-drum shaft *j* there is mounted a windlass-drum *n* and a spur-gear *o* fixedly connected with the latter and 50 in mesh with a pinion *p* mounted upon the intermediate shaft *k*. Upon the intermediate shaft *k* there is mounted a spur-gear *q* which meshes with a pinion *r* fastened upon the topmost or operating-shaft *m*, the front

end of which projects beyond the front upright *s* of the subframe *i* and is adapted to be engaged by the operating crank *s*. Upon the topmost shaft *m* there is also mounted a brake-disk *t* which is controlled by a brake-strap *u* or other suitable brake-members. Mounted free to slide in the side standards *f* of the main frame is a load-carrying platform *v* to which is fastened one end of a cable *w* the other end of which is wound around the windlass-drum *n*. The 55 parts hereinbefore described are old and well-known and are shown in the United States patent granted Thomas James McCarthy, No. 854,961, granted May 28, 1907.

At the upper end of each of the side members *f* of the main frame there is fastened a horizontally-disposed plate *x* to the outer end of which is pivotally connected or hinged at *y* a similar horizontally-disposed plate *z* which is fastened to the lower end 70 of one of the side members *f'* of the intermediate section 2. The main frame and the latter are held normally locked together by means of a locking-bolt 3 and nut 4. In an entirely similar manner the upper section 5 is hinged to the intermediate section 2 and is held normally locked by a locking bolt and nut; and it will be understood that the 75 number of sections is not limited but may be increased or decreased at will. The side members *f'*, *f''* of the sections 2, 5, are in line with the standards or side members *f* of the main frame and form with the latter a continuous guideway for the load-carrying platform *v*. Furthermore, the sections 80 are braced by horizontal and inclined braces *g*, *h*, substantially in the same manner in which the main frame is braced. In the main frame and in each of the sections there is fastened to one of the horizontal frame 85 members *g* a centrally-disposed sheave-bracket 6 which is U-shaped and in the lower end of which there is mounted a removable shaft 7 which is adapted to support the sheave 8 over which passes the cable *w*. 90 The sheave-shaft 7 is held in place by means of cotter pins 9.

When it is desired to move the tiering machine from room to room, it will be found generally necessary to vary the 105 height of the machine so that it may pass through the doorway by means of which the two rooms communicate. To vary the

height of the machine, one of the cotter pins 9 is removed and the sheave-shaft 7 is taken out of the topmost sheave-bracket 6 and placed together with the sheave 8 in one of 5 the lower brackets. Then the locking nuts 4 are loosened and the locking bolts 3 are removed, after which the uppermost section 10 is swung into the dotted line position shown in Fig. 1. If after lowering the topmost section it is found that the height of the machine is still too great to enable it to pass through the doorway, the intermediate section 15 is swung upon its hinges γ in an entirely similar manner. After the machine has passed through the doorway into the proper room, the lowered section or sections 20 may be raised into their proper position. Of course, the provision of the hinged extension sections makes it possible to vary the reach or range of action of the tiering machine, as well as adapts it for being moved from room to room through the doorways by means of which the same communicate. 25 In accordance with the provisions of the patent statutes I have described the principle of operation of my invention, together with the apparatus which I now consider to represent the best embodiment thereof; 30 but I desire to have it understood that the apparatus shown is only representative and that the invention can be carried out by other means.

I claim:

1. A sectional tiering machine having a 35 main frame provided at its upper end with a laterally-extending arm; an extension section provided at its lower end with a laterally-extending arm, said arms being hingedly connected and said section being 40 normally in prolongation of said main frame; a load-carrying platform mounted free to move in said frame and section; and mechanism for raising said platform.

2. A sectional tiering machine having a 45 main frame provided at its upper end with a laterally-extending arm; an extension section provided at its lower end with a laterally-extending arm, said arms being hingedly connected and said section being 50 normally in prolongation of said main frame; a load-carrying platform mounted free to move in said frame and section; a cable one end of which is attached to said load-carrying platform; mechanism for 55 winding up the other end of said cable; and a movable sheave over which said cable runs and which is transferable back and forth between said section and main frame.

Signed at Jersey City, in the county of 60 Hudson and State of New Jersey, this seventeenth day of April, 1913, in the presence of the two undersigned witnesses.

WILLIAM EDWARD BOEHCK.
